DESIGN FOR A DESK CALENDAR

Carlyle N. Montanye, Glyndon, Md.

Application October 29, 1936, Serial No. 65,593

Term of patent 7 years

To all whom it may concern:

Be it known that I, Carlyle N. Montanye, a citizen of the United States of America, residing at Glyndon, county of Baltimore, and State of Maryland, have invented a new, original, and ornamental Design for a Desk Calendar, of which the following is a specification, reference being had to the accompanying drawing, forming a part thereof, wherein:

Figure 1 is a front elevation of a desk calendar, showing my new design.

Figure 2 is a top plan view.

I claim:—

The ornamental design for a desk calendar, as shown.

CARLYLE N. MONTANYE.
